FILING SYSTEM

Filed Aug. 4, 1926

Inventor
ROBERT PHILLIP GARROW,
By *Taubman* *Taubman*
Attorneys

UNITED STATES PATENT OFFICE.

ROBERT PHILIP GARROW, OF CHESTERFIELD, ENGLAND.

FILING SYSTEM.

Application filed August 4, 1926, Serial No. 127,153, and in Great Britain March 8, 1926.

This invention relates to improvements in filing systems, more particularly to a tab or mount for filing sheets, cards or the like of the type which is attached to a card and comprises a distance piece adapted to slidably engage guides and attached to the cards by a hinged or flexible member positioned near each end of the card, said distance piece projecting on each side of the hinged or flexible member.

Hitherto the distance pieces of such tabs or mounts have extended from end to end along the edge of the sheet or the like for at least the full width of the sheet whether attached by one or by more flexible hinged members and consequently the length of the distance piece has always been governed by the size of the sheet. Consequently such distance pieces have, disadvantageously, had to be made in various lengths to fit the particular sizes of sheets to which they were required to be attached. Therefore, these forms of tabs do not possess universality of application and the object of this invention is to provide an improved tab or mount overcoming this disadvantage whereby a tab or mount can be universally applied to any sheet, card or the like irrespective of its size.

According to this invention therefore, a tab or mount of the above indicated kind is less than half the length of the adjacent edge of the sheet, card or the like to which it is to be attached, the distance piece being slightly longer than the hinged or flexible member and attachable to either end of the sheet, card or the like by the hinged or flexible member so as to position one end of the distance piece flush with one edge of said sheet, card or the like, the distance piece being adapted to engage a guide located between said end and the sheet, card or the like.

Referring to the drawings filed herewith:

Fig. 1, is a perspective view of one form of means for filing cards made in accordance with this invention.

Fig. 2, is a detail view on an enlarged scale of a tab or mount for the cards.

Fig. 3, is a fragmentary section also to an enlarged scale on the line A—B, Figure 1.

50 *a, a* are a plurality of sheets, cards, folders, or the like (hereafter referred to, for the sake of brevity, as cards) each provided at one side with two tabs or mounts in the form of a distance piece *b* made, for example, of cel-

luloid or any other suitable material say 55 about 1½" long, ¼" wide and of sufficient thickness to be fairly rigid, one distance piece being attached to one end and one to the other end of the upper edge of the card by a central flexible member *c*, for example 60 of gummed linen tape, which may be additionally secured to the distance piece by a staple *d*, one end of each distance piece *b* being flush with one side edge of each card *a* as shown. Each card can, therefore, be 65 turned on the flexible strips in the manner of a hinge. *e, e* are drawers or trays (hereafter referred to as trays) in which the cards *a* are adapted to be contained, and in each tray two parallel guides *f* are provided, one each 70 at two opposite sides of the trays *e* and the distance pieces *b* are adapted to engage these guides *f* in such a manner that said guides are located between one end of the distance pieces and the cards, whereby the said cards 75 can be slid along the trays, by reason of the distance pieces slidably engaging the guides, whilst they can also be turned over on the flexible members *c* from one side to the other.

A very convenient form of guide *f* may 80 comprise, as shown, a strip of celluloid or other suitable material mounted slightly above the surface of each tray *e* so that the space between the guide and the surface of the trays forms a space deep enough to receive the distance pieces *b* lying adjacent one another on the bottom of the trays and when so positioned, the cards *a* are consequently positioned adjacent one another each with its free edge visibly exposed to an extent 85 corresponding to the width of the distance pieces *b* and thereby effecting visibility of any written or printed matter on the said exposed edge of the cards. The cards can be turned 90 over to rear or front on the flexible members 95 *c* through an angle of 180° about the distance pieces and any card may be written upon either side.

Suitable stops in appropriate positions or at the ends of the guides may be provided for 100 preventing the distance pieces *b* passing beyond the limit of the guides and these stops may be constituted, as shown, for example, by a fillet *g* provided in each tray at the front and forming a termination to the front 105 end of the guides whilst, owing to their inclined upper face, said fillet also conveniently serves as a slope or inclined support for the

cards *a* which facilitates handling in turning over the undermost cards at the front of the tray.

It is to be understood that the cabinet and trays can be made of any suitable material and further, the trays may be fitted endwise or sidewise in the cabinet.

The trays, whether inserted edgewise or endwise into the cabinet, are supported in any well-known manner and may have handles or knobs *h* and label holders *j* on the front.

It will, therefore, be seen that tabs made according to this invention are symmetrical in form and universal in their application either to various sizes of cards or as regards their position on the cards.

What I claim and desire to secure by Letters Patent is:—

1. For filing systems an attachable card having a tab of the kind described, comprising a distance piece less than half the length of the adjacent edge of said card, a flexible member attached to the distance piece, said distance piece projecting on each side of the flexible member, one end of the distance piece being flush with one edge of the card and one

end only of the distance piece being adapted to engage a guide located between said end and the card.

2. For filing systems an attachable card having a distance piece less than half the length of the adjacent edge of the card, a flexible member attached to the distance piece by adhesive and a staple, said distance piece projecting on each side of the flexible member, one end of the distance piece being flush with one edge of the card and one end only of the distance piece being adapted to engage a guide located between said end and the card. 40

3. In filing systems, cards each provided with two tabs, each tab comprising a distance piece less than half the length of the adjacent edge of the card, a flexible member attached to each distance piece, said distance pieces projecting beyond the sides of the flexible members, one end of each distance piece being flush with an edge of the attached card and adapted to engage a guide located between it and the card and the other ends 50 of the distance pieces being free.

In testimony whereof, I affix my signature.

ROBERT PHILIP GARROW, M. D.
